TIME DELAY RELAY CIRCUIT

Renato Di Giuseppe, Rome, Italy; vested in the
Alien Property CustodianApplication October 4, 1940, Serial No. 359,791
In Italy November 11, 1939

1 Claim. (Cl. 175—320)

The present invention relates to control means for an electric timing circuit employing two relay windings poled to magnetically oppose each other, and electrical circuit time delay means therefor.

It is already known that a delayed electrical control may be obtained by means of a condenser inserted in a relay circuit so arranged as to maintain the relay closed by means of the discharge current, and connected to a commutator or contact breaker, until the intensity of such current of discharge has fallen below a certain predetermined value.

According to the present invention, use is also made of the condenser, but the circuit is so arranged that the relay operating the switch or contact breaker to be controlled, operates during the charging of the condenser until the charging current, supplied from a constant voltage source, falls below a certain predetermined value; the system of time-delay control so obtained being used in conjunction with means adapted to repeat periodically the operation at predetermined intervals of time, always equal to each other.

The invention comprises essentially an electric circuit in which is inserted a switch comprising pairs of two or more contacts controlling a relay of normal type, a condenser traversed by a current of sufficient intensity for maintaining attracted the armature of said relay during a predetermined time, said relay being connected by a key adapted to open one pair of contacts for starting the charge of the condenser, and adapted to close the other pair of contacts which re-establishes the circuit in place of the key.

The interval of time during which the circuits maintain the relay closed constitutes the measured unit of time.

The device according to the present invention is shown schematically in various embodiments and by way of example in the attached drawing, 49 in which:

Fig. 1 shows a circuit in which a relay is attracted immediately upon application of voltage to its winding and remains attracted for a given time after the operating switch has been opened. (Time-delay dropout relay.)

Fig. 2 shows a circuit similar to that shown in Fig. 1, arranged so as to compensate any variations of voltage of the supply current.

Fig. 3 shows a circuit similar to that shown in Fig. 2, comprising a time-delay relay which is energized into actuated position after a determined time from its connection, said actuated condition ceasing immediately upon its disconnection. (Time-delay pickup relay.)

Fig. 4 shows a circuit similar to those illustrated in Figs. 2 and 3, but provided with a time-delay relay retarding its action both on its connection and disconnection. (Time-delay pickup and dropout relay.)

The timed circuits which I describe may be arranged to actuate any conventional electrical impulse actuatable instrument as a counting or recording system.

Fig. 1 shows schematically a circuit so arranged between supply mains that the relay armature provided is attracted immediately upon its connection, and continues to be attracted for a determined time after the voltage supply has been disconnected. (Time-delay dropout relay.) In such circuit, the relay winding 1, is energized immediately on closing button 17, while condenser 18 is short circuited by said contact button 17, and is thereupon discharged. When the circuit is opened, through the opening of contact button 17, the relay winding 1 continues to be traversed by current, until the value of said charging condenser current falls below a certain determined value.

Fig. 2 shows schematically a circuit similar to that shown in Fig. 1, and connected across supply mains, but provided with means adapted to compensate any variations of voltage of the supply current. These means consist in forming the relay on an E shaped core, comprising two windings 14 and 15 on the respective outer legs, and an oscillating bar armature 16 pivoted between said core windings on the legs, one of which may be connected as the relay winding 1 shown in Fig. 1, and the other may be shunted across the supply voltage with an adjustable resistance connected in series, thus acting as an opposing force.

With the arrangement just described, both the actuating force of the relay, due to the charging current of condenser 18, and the opposing force which causes the relay contact and the condenser to be disconnected, when said actuating force decreases, are proportional to the voltage of the current, i. e., they vary similarly with the variations of the latter, and consequently the operation of the device depends solely on the electric characteristics of the circuit, and so remains practically constant even during any variations of the voltage.

In the circuit shown in Fig. 2, the rheostats 19 and 20 are used for adjusting, within certain limits, the time characteristic of the circuit.

Fig. 3 shows a circuit similar to that shown in Fig. 2, with which however the opposite effect is obtained, i. e., a retardation of the closing of the

relay (time-delay pickup relay). In this circuit, winding 14 is the active one, while winding 15 provides the opposing force; these two windings are so designed that on pressing the key 21 from its normal spring urged position as shown, the winding 14 is connected and the normally closed short circuit across condenser 18 is opened and condenser 18 starts to charge through winding 15 energizing the latter, but the force produced by winding 14 is not sufficient for attracting immediately the movable armature 16, and consequently a time τ has to pass between said connection and the actual attraction of armature 16, after which the current charge of condenser 18, drops to such a low value, that the current traversing the winding 15 falls below and is overcome by that traversing the winding 14. Also in this case the time-delay depends on the values of condenser 18 and resistances 19 and 20.

The relay shown in Fig. 3 has a quick return to unactuated position, viz.; as soon as key 21 is released, the movable pivoted armature 16 is immediately attracted again by the winding 15.

The circuit shown in Fig. 4 is a time-delay pickup and time delay dropout relay. In fact, in this circuit, on pressing the button 21, the operation above described for the circuit of Fig. 3 is obtained, and on releasing said key 21, the operation described for the circuit of Fig. 2 is obtained. The values of the two time-delays depend on the values of the condensers 18 and 23 and of the resistances 19, 20 and 22. Condenser 18 is connected across the fixed contacts of switch 21 which make connection to the restraining winding 15, and by its charging current causes winding 15 to restrain the actuation of relay armature

16 when button 21 is depressed. Condenser 23 is connected across the fixed contacts of switch 21 which make connection to the actuating winding 14, and by its charging current delays the reduction of the current through actuating winding 14 to armature releasing value when button 21 is released from depressed position.

It will be understood that the controlling circuit of an electrically actuatable instrument whose operation is to be controlled with time delay characteristics, may be connected to the controlled contact of armature 16.

What I claim is:

15 In control means for an electric timing circuit, electromagnetic relay means having a set of controlled contacts and further having an operating and a restraining winding magnetically opposing each other, a switch having two positions and having a first pair and a second pair of controlled contacts and adapted in a given position to selectively connect together either said first pair or said second pair of contacts but not both pairs, a source of electrical energy, a first contact of each of said pairs being connected to a first 20 terminal of said source, the second contact of said first pair being connected to a first terminal of said operating winding and the second contact of said second pair being connected to a first terminal of said restraining winding, the second 25 terminals of said windings being connected to the second terminal of said source, and a pair of electrical time delay circuits each comprising electrical energy storing means respectively connected 30 across said pairs of contacts respectively.
